UNITED STATES PATENT OFFICE.

PERCIVAL W. JONES, OF WARWICK, RHODE ISLAND.

HOOK.

Application filed March 26, 1927. Serial No. 178,677.

This invention relates to an improved construction bracelet end hook for attaching the ends of a bracelet to a wrist watch; and has for its object to provide a construction by 5 which no open space is left between the hook and the watch when the hook is in engagement with the bail of the watch to thereby present a more attractive appearance when the same is in position on the wrist of the 10 wearer.

A further object of the invention is to provide a closing portion extending between the bail engaging portion of the hook and the watch by doubling back the sheet 15 stock of the shank of the hook closely upon itself before extending the same rearwardly to engage the bail of a watch.

A still further object of the invention is the provision of a tongue for closing the 20 hook which may be easily and quickly assembled without solder or tools in the body of the hook and secure in position therein.

With these and other objects in view, the invention consists of certain novel features 25 of construction, as will be more fully described, and particularly pointed out in the appended claims.

In the accompanying drawings:

Figure 1 is a plan view of a wrist watch 30 showing the hooks of my improved construction attached to the bails thereof.

Figure 2 is a perspective view of the body of the hook.

Figure 3 is a perspective view of the 35 tongue for closing the hook-shaped portion of the device.

Figure 4 is a perspective view of the bottom of the device showing the tongue and the body assembled.

Figure 5 is a section on line 5—5 of Figure 4.

Figure 6 is a section on line 6—6 of Figure 5.

Figure 7 is a section on line 7—7 of Figure 5.

Figure 8 is an enlarged side elevation of the hook in engagement with the bail of a wrist watch the latter being fragmentally shown.

It is found desirable in the use of bracelet end hooks for attaching the ends of a bracelet to a wrist watch to provide a construction to prevent a space occurring between attached parts to expose the wrist of the 55 wearer when viewing the bracelet from the top, but to rather present an extended

metal surface which may be suitably ornamented; and in order to provide a hook which will closely fit the edge of the wrist watch, I have so formed the watch bail engaging portion at a position moved inwardly from the edge of the hook so as to leave an extended portion to closely engage the edge of the watch and prevent an opening appearing between the hook and the watch; and the following is a detailed description 60 of the present embodiment of this invention and showing one construction of bracelet hook by which this advantageous result is 65 accomplished:

With reference to the drawings, 10 designates a wrist watch having bails 11 with bracelet end hooks 12 connecting the bracelet links 13 thereto, the hooks 12 each comprising a body 14 having side walls 15 folded 70 inwardly to provide a bottom wall 16 with inturned fingers 17 extending inwardly from the edge thereof toward the top wall. The top wall of the bracelet is extended to form a shank 18 which is doubled back sharply 75 upon itself as at 19 to extend rearwardly beneath this shank portion as at 20 and then downwardly to form a wrist watch bail engaging hook 21. When the hook 21 is in engagement with the bail 11 the portion 19 extends beyond the bail a substantial distance to closely abut the edge 22 of the 80 watch to prevent an open space occurring between the hook and the watch, as clearly 85 illustrated in Figures 1 and 8.

It is of course apparent that where the watch is of a shape different from that illustrated in the drawing that the end portion 19 of the hook will be correspondingly different to closely engage the edge of the 90 watch to accomplish the desired result.

A tongue 23 closes the opening to the hook 21 and is doubled back upon itself to provide a resilient portion 24 which is arc shaped and provided with flanges 25 notched 95 as at 26 to receive the fingers 17 carried by the bottom wall 16 of the body to securely position the tongue in the body. The resiliency of the arc shaped doubled back portion 24 serving to hold the notches 26 in 100 engagement with the fingers to prevent longitudinal movement of the tongue member.

From the construction above described it will be apparent that the tongue may be easily positioned within the body by merely 110 inserting the same between the side walls 15, and moving the same rearwardly until the

2
fingers 17 snap into the notches, to prevent further longitudinal movement. The tongue 23 is prevented from lateral movement by means of shoulders 27 on either side to engage the flanges 25 which flanges closely fit the side walls 15 of the body to prevent the entire tongue member from lateral movement relative to the body.

From the foregoing, it will be seen that I have provided a hook the construction of which performs the desired result of closing the opening between the hook and the watch and one by which the tongue for closing the hook may be quickly and easily assembled without the use of solder or other special tools and by the use of a tongue of such construction, the outer surface of the body of the hook may be suitably ornamented by the use of processes employing without affecting the resiliency of the spring tongue which may be snapped into position after the heating operations on the body have been performed.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A bracelet hook comprising a body having a shank formed into a hook at one end for engaging the bail of a wrist watch and means integral with the shank for extending a substantial distance beyond the bail engaging portion of said hook to close the opening between the watch and the hook.
2. A bracelet hook comprising a body having a shank formed into a hook for engaging a watch bail and having a portion folded upon itself and extending beyond the bail engaging the inner surface of the hook to close the opening between the hook and a watch to which it may be attached.
3. A bracelet hook comprising a body having a shank doubled back upon itself and extending closely along its under surface a

short distance and then opening downwardly 50 into a hook to engage the bail of a wrist watch the doubled back portion closing the opening between the hook and the watch.

4. A bracelet hook comprising a body having a shank formed into a hook, a tongue for closing the hook having a portion doubled back upon itself and of a size to engage the opposite sides of the body and centrally align the tongue with relation thereto.

5. A bracelet hook comprising a body having side walls and a shank hook shaped at its end, a tongue for closing the hook shaped end and having a doubled back portion with side flanges engaging the side walls of said body and formations on said side flanges 65 and body to lock the tongue in position.

6. A bracelet hook comprising a body having top, bottom, and side walls, and a shank extending from the top wall hook shaped at its end, a tongue for closing said end and having a doubled back resilient portion tending to assume an arc-shape and forcing the tongue against the bottom wall, and means to lock the tongue in the body.

7. A bracelet hook comprising a body having top, bottom and side walls, a shank extending from the top wall formed into a watch bail engaging hook inwardly extending fingers carried by one of the walls of said body, a tongue for closing the hook and having a folded back resilient portion with recesses to be engaged by said fingers upon the moving of said tongue longitudinally of the body into position.

8. A bracelet hook comprising a body having top, bottom and side walls, a shank extending from the top wall formed into a watch bail engaging hook, fingers on the bottom wall extending inwardly toward the top wall, a tongue for closing the hook having a folded back resilient portion with side flanges notched on their edges to receive said fingers upon moving said tongue longitudinally of the body into position the resiliency of said portion holding the notched flanges 95 in engagement with said fingers.

In testimony whereof I affix my signature.
PERCIVAL W. JONES.
